UNITED STATES PATENT OFFICE.

A. VAN TRUMP, OF LANCASTER, OHIO.

IMPROVEMENT IN SUGAR-CANE MILLS.

Specification forming part of Letters Patent No. 23,128, dated March 1, 1859.

To all whom it may concern:

Be it known that I, A. VAN TRUMP, of Lancaster, in the county of Fairfield and State of Ohio, have invented a new and useful Improvement in Sugar-Cane Mills; and I do hereby declare that the following is a full, clear, and exact description of the same, reference being had to the accompanying drawings, forming a part of this specification, in which—

Figure 1 is an end view of a cane-mill with my improvements applied to it, and Fig. 2 is a vertical longitudinal section of the same.

Similar letters of reference in each of the several figures indicate corresponding parts.

The nature of my invention consists in the combination, in a sugar-cane mill, of two or more intermediate small feed-rollers with four or more large crushing-rollers, said small feed-rollers being arranged between the large crushing-rollers at such a point that their peripheries work in concert on the same line as do the peripheries of the large crushing-rollers, and thus form a support and act as a feed-motion, at the center of the machine, to the ends of the cane-stalks as soon as they emerge from between the first pair of crushing-rollers, and until they pass in between the second pair of crushing-rollers. By this feature of my invention the fatal defect in cane-crushing machines which employ four or more rollers is overcome, said defect being the vertical passage of the ends of the stalks as soon as they escape through the first pair of rollers down between the lower rollers of the first and second pair, and a consequent chokage and stoppage, and very often breakage, of the machine. The great benefit of my improvement can hardly be summed up in words, when the serious obstacles which the above defect presents to the perfect crushing of sugar-cane by rollers not having my simple but effective improvement combined with them are taken into consideration.

My invention consists, second, in the particular arrangement, hereinafter specified, of the sustaining-frame, crushing and feed rollers, and gearing, whereby great strength and steadiness in the parts, perfection in the operation, and facility of adjustment are obtained.

To enable others skilled in the art to make and use my invention, I will proceed to describe its construction and operation.

A represents the frame of the press. This frame consists of two strong side plates, *a a*, with horizontal flanges *b b*, a base-plate, *b'*, which has a flange, *c*, on its upper side, for the flanges to bear against both laterally and longitudinally, and capping-plate *e*, as shown. These plates are all firmly bolted together by vertical bolts *f f* and *g g*. By thus constructing the frame great firmness and strength are obtained, and the great strain which comes upon the rollers will not affect it.

B B' B' are the crushing-rollers. Those *B B* are arranged over one another, and are the preparatory crushing-set. Those *B' B'* are similarly arranged, and are the finishing-set. Each of the rollers has its bearing in boxes *g' g'*, fitted in the side plates, *b b*, as shown. The bearing-boxes of the lower roller of each set are made to rest on wedges *h h' h'' h'''*, so that by pulling out the wedges *h h'* and driving in *h'' h'''* these rollers can be raised and brought nearer to the upper rollers. The effect will be just the reverse by pulling out the wedges *h'' h'''* and driving in *h h'*.

C C are the small intermediate feed and supporting rollers. They are arranged so as to close up the vertical space between the two sets of rollers, and so that their peripheries work in concert or operate upon the cane-stalk in the same line as do the peripheries of the large crushing-rollers, and thus insure a straight and certain passage of the stalks through the machine. These rollers act as supports, guides, and crushers, and also as a feed-motion. The large crushing-rollers have spur-wheels *D D D D* on the ends of their shafts, and the two sets are combined by the spur-wheel *E*, as shown in Fig. 1. On the opposite ends of the lower one of the first or preparatory set of crushing-rollers a large spur-wheel, *F*, is arranged. This roller gears into a pinion, *G*, of the lower one of the intermediate set of feed-rollers. *H* is a driving-pulley or spur-wheel on the shaft of the lower roller of the preparatory set of crushing-rollers. By this arrangement of gearing it will be evident that if the power is applied to the pulley *H* all the rollers will be set in motion, and that the cane-stalk will be passed horizontally through or between the three sets of rollers.

It should be remarked that the effect of the small rollers upon the stalks is made equal to

that of the large rollers, by reason of their speed being much quicker than the speed of said rollers.

What I claim as my invention, and desire to secure by Letters Patent, is—

The combination, in a sugar-cane mill, of two or more intermediate small feed-rollers, C C, with four or more large crushing-rollers, B B B' B', substantially as and for the purposes set forth.

The above specification of my improvement in sugar-cane mills signed by me this 8th day of February, 1859.

A. VAN TRUMP.
